CLAIM

The ornamental design for an ergonomic retaining clip, as shown and described.

DESCRIPTION

FIG. 1 is a perspective view of an ergonomic retaining clip embodying our design;

FIG. 2 is a side elevation view as seen from the left side of FIG. 1;

FIG. 3 is a side elevation view as seen from the right side of FIG. 1, opposite that of FIG. 2;

FIG. 4 is a top plan view thereof;

FIG. 5 is a bottom plan view thereof;

FIG. 6 is a front elevation view thereof; and,

FIG. 7 is a rear elevation view thereof.
